UNITED STATES PATENT OFFICE

NOAH S. HARTER, OF WAUKEGAN, ILLINOIS

DESIGN FOR WIRE FENCE FABRIC

Application filed June 4, 1929. Serial No. 31,542. Term of patent 14 years.

To all whom it may concern:

Be it known that I, NOAH S. HARTER, a citizen of the United States, residing at Waukegan, in the county of Lake and State of Illinois, have invented a new, original, and ornamental Design for Wire Fence Fabric, of which the following is a specification, reference being had to the accompanying drawings, forming part thereof.

I claim:

The ornamental design for wire fence fabric, as shown.

NOAH S. HARTER.
